VESSEL WITH CRIMPED OR CROWN CAP AND CAP REMOVER

Filed May 14, 1930

UNITED STATES PATENT OFFICE

FRANK LEE DARLING, OF BALTIMORE, MARYLAND

VESSEL WITH CRIMPED OR CROWN CAP AND CAP REMOVER

Application filed May 14, 1930. Serial No. 452,377.

My invention relates to certain new and useful improvements in means for sealing bottles, jars and other vessels using crimped caps.

5 Heretofore when crimped caps have been employed for sealing vessels it has been found almost impossible to seal the bottles with tin foil coverings over the caps and bottle necks since the sharp edges of the skirts of the caps project through the foil causing it to tear. This is particularly noticeable on bottles used for containing drinks such as certain high grades of ginger ale and alcoholic beverages.

Further, with the bottles and caps now 15 commonly used, persons frequently cut their hands on the rough edges of the caps in handling the bottles; it is therefore an object of my invention to provide a bottle and cap combination in virtue of which such objectionable 20 features may wholly be eliminated.

Further, it is an object of the invention to provide a bottle and cap combination with a 25 remover of the type disclosed in my application Serial No. 315,017 which is of such construction that a sealing covering of tin foil or the like may be placed over the opener or over the cap and opener, or a paper seal may be employed around the neck over the opener if desired.

30 Further, in manufacturing bottles employing the recesses in the neck ring of the bottle in which the ends of my remover are held, it has been found that sometimes the lifting of the parison by the neck ring of the mold during the formation of the bottle causes distortion in the recesses in the mouth ring which sometimes interferes with proper sealing; it is therefore an object of the present invention to provide a bottle or other similar vessel

35 with a second ring (called a neck ring) located adjacent to the mouth ring of the bottle by which second or neck ring the parison may be held by the neck ring of the mold, thereby taking off the strains from the mouth ring of the bottle which tend to cause distortion of the indented part of the mouth ring,

40 Further, it is an object to provide a bottle with a sealing ring beneath the bottom edge of the crown, which ring lies so close to the crown that it not only serves as a guard for

the sharp edges of the crown but also prevents the insertion of an implement between the crown and the ring by which the crown can be prized off from the bottle, thereby compelling the use of my crown remover; a further object is to provide such a sealing ring (neck ring) as above described which will also serve as a fulcrum or abutment for the edge of the cap while the cap is being lifted by the remover, thereby facilitating the loosening of 55 the cap from the bottle.

Further, it is an object to provide a bottle or other crowned vessel having my cap remover, with an auxiliary or neck ring located below the mouth ring of the bottle, 60 which auxiliary ring has under-cut recesses for the reception of the remover legs, thus insuring the holding of the remover snugly against the bottle neck during capping of the bottles and also enabling the bottles to be 65 shipped from the glass factory with the removers attached if desired.

Other objects will in part be obvious and in part be pointed out hereinafter.

To the attainment of the aforesaid objects 70 and ends, the invention still further resides in the novel details of construction, combination and arrangement of parts, all of which will be first fully described in the following detailed description, then be particularly 75 pointed out in the appended claims, reference being had to the accompanying drawings, in which:

Figure 1 is a perspective view of a bottle with my invention applied, a tin foil seal 80 being placed over the cap and neck.

Figure 2 is a front elevation on an enlarged scale showing another way of "sealing" the bottle.

Figure 3 is an elevation of the parts shown 85 in Figure 2 taken from a position 90° around the bottle showing the cap in process of removal and the seal being broken.

Figure 4 is a detail view showing a cap being removed, the cap being shown in section and the bottle top in elevation.

Figure 5 is a detail elevation of the bottle neck with the cap removed.

Figure 6 is a horizontal section on the line 6-6 of Figure 5. 100

Figure 7 is a horizontal section on the line 7—7 of Figure 5.

In the drawings, in which like numerals of reference indicate like parts in all of the figures, 1 represents the vessel (a bottle being illustrated for purposes of illustration only) having the mouth ring 2 which has a flush unbroken mouth surface 3 against which the cork insert 18 of the cap 16 may bear to effect an air-tight seal. The mouth ring 2 has its under edge 4 flat to serve as a holder for the crimps 17 of the skirt of the cap 16.

The mouth ring is also provided with a pair of indentations 7—8 spaced apart, these indentations being in the general form of an inverted L and having their adjacent surfaces under-cut as at 9 and 10, the indentations having vertical parts 7 as shown.

Beneath the mouth ring 2 is located a neck ring 5 which has several functions; first, to act as a guard for the edge of the skirt 17 of the cap 16 and prevent one cutting one's hand on the sharp edges of the cap; secondly, it functions as a means to prevent the removal of the cap by any other instrument than the remover 13 provided with the bottle; thirdly, it serves as an auxiliary means for retaining the remover 13 in place on the bottle before the cap is applied.

The auxiliary or neck ring 5 has vertical slots 11 for the reception of the legs 14 of the remover 13, the hook ends 15 of which remover engage in the recesses 7—8, the vertical parts 7 of the recesses aligning with the grooves 11, the latter being undercut as at 12 similarly to the undercut 10 of the mouth ring.

As shown in Figure 1, the bottle and cap may have its neck covered with a sealing envelope 19 of suitable foil, or as shown in Figure 2, a strap seal 20 may be placed around the neck of the bottle over the remover 13. The provision of the sealing envelope or seal possesses the advantage with the present construction that the opener will be shielded from any obstacles which might tend to move it and in this manner displace the cap. The seal thus performs the important function of a guard effectively holding the opener against unintentional opening forces.

From the foregoing description, taken in connection with the accompanying drawings, it will be noticed that the diameter of the ring 5 is not less than the outer diameter of the skirt 17 when crimped tight and is preferably just a trifle greater in diameter, thus the diameter of the ring 5 and the diameter of the crimped skirt 17 may be substantially equal.

It is further to be noted that when the cap has been crimped tight on the bottle the lower edge of the skirt 17 will rest practically in contact with the ring 5, the upper surface of which ring is made flat in order to enable the cap to lie against it.

In order to remove the cap it is only necessary to lift up on the remover 13 which at once breaks the seal 20 or 19 as the case may be, and prize the cap from the bottle. In this operation the portion of the edge of the cap diametrically opposite the remover will rest on the ring 5 as a point of fulcrum, thus facilitating the rapid and easy removal of the cap by means of the remover provided therefor. (See Figs. 3 and 4.)

Other advantages of the invention will be clear to those skilled in the art.

While I have disclosed my invention in its specific embodiment as applied to a bottle it is evident that it may also be applied to vessels of other shapes.

What I claim is:

1. In combination, a vessel having a mouth ring adapted to receive a crimped cap provided with the usual skirt, a crimped cap fitted over said mouth ring, a cap remover having a portion housed within the confines of the cap, and a neck ring below said mouth ring providing a shoulder at its upper edge substantially in contact with the lower edge 90 of the cap skirt when the cap is in operative sealing position on the vessel.

2. In combination, a vessel having a mouth ring adapted to receive a crimped cap provided with the usual skirt, a crimped cap fitted over said mouth ring, a cap remover having a portion housed within the confines of the cap, and a neck ring below said mouth ring providing a shoulder at its upper edge substantially in contact with the lower edge 100 of the cap skirt when the cap is in operative sealing position on the vessel, said neck ring being of a diameter not less than that of the cap at the edge of the skirt.

3. In combination, a vessel having a mouth ring adapted to receive a crimped cap provided with the usual skirt, a crimped cap fitted over said mouth ring, a cap remover having a portion housed within the confines of the cap, and a neck ring below said mouth ring providing a shoulder at its upper edge substantially in contact with the lower edge 110 of the cap skirt when the cap is in operative sealing position on the vessel, said neck ring having a groove receiving a portion of the remover.

4. In combination, a vessel having a mouth ring adapted to receive a crimped cap, a crimped cap fitted over the mouth ring and provided with the usual crimped skirt, a cap remover comprising a strip of resilient material having a reverse bend and having its ends separated and housed within the confines of said cap, the remover being pendent along the side of the vessel neck, and a neck ring on said vessel providing a shoulder at its upper edge substantially in contact with the lower edge of the cap skirt when the cap is in operative sealing position on the ves- 130

sel, said neck ring having a pair of spaced grooves receiving said remover.

5. In combination, a vessel having a mouth ring adapted to receive a crimped cap, a crimped cap fitted over the mouth ring and provided with the usual crimped skirt, a cap remover comprising a strip of resilient material having a reverse bend and having its ends separated and housed within the confines of said cap, the remover being pendent along the side of the vessel neck, and a neck ring on said vessel providing a shoulder at its upper edge substantially in contact with the lower edge of the cap skirt when the cap is in operative sealing position on the vessel, said neck ring being of a diameter not less than that of the cap at the edge of its skirt.

10. In combination with a vessel having a mouth ring adapted to receive a skirted cap, said mouth ring having spaced indentations below the top edge of the vessel, a cap remover having an end held in said indentations within the confines of the cap when the cap is applied to the vessel, and a neck ring on said bottle beneath the mouth ring having a shoulder at its upper edge designed to engage the lower edge of the cap when in operative sealing position on the vessel.

15. In combination, a vessel having a mouth ring adapted to receive a crimped cap, a crimped cap fitted over the mouth ring and provided with the usual crimped skirt, a cap remover comprising a strip of resilient material having a reverse bend and having its ends separated and housed within the confines of said cap, the remover being pendent along the side of the vessel neck, and a neck ring on said vessel providing a shoulder at its upper edge substantially in contact with the lower edge of the cap skirt when the cap is in operative sealing position on the vessel, said neck ring being of a diameter not less than that of the cap at the edge of its skirt and being grooved to receive the pendent remover.

30. 7. In combination, a vessel having a mouth ring adapted to receive a crimped cap provided with the usual skirt, a crimped cap fitted over said mouth ring, a cap remover having a portion housed within the confines of the cap, and a neck ring below said mouth ring providing a shoulder at its upper edge substantially in contact with the lower edge of the cap skirt when the cap is in operative sealing position on the vessel and a seal enclosing the cap skirt and remover.

35. 8. In combination, a vessel having a mouth ring adapted to receive a crimped cap provided with the usual skirt, a crimped cap fitted over said mouth ring, a cap remover having a portion housed within the confines of the cap, and a neck ring below said mouth ring providing a shoulder at its upper edge substantially in contact with the lower edge of the cap skirt when the cap is in operative sealing position on the vessel and a flexible seal covering the cap and cap remover and substantially encircling the vessel neck.

40. 9. In combination, a vessel having a mouth ring adapted to receive a crimped cap provided with the usual skirt, a crimped cap fitted over said mouth ring, a cap remover having a portion housed within the confines of the cap and having another portion projecting along the bottle neck beneath

the cap, and a neck ring below said mouth ring providing a shoulder at its upper edge substantially in contact with the lower edge of the cap skirt when the cap is in operative sealing position on the vessel and a seal overlying the projecting portion of the cap remover and holding it to the bottle neck against accidental displacement.

45. 10. In combination with a vessel having a mouth ring adapted to receive a skirted cap, said mouth ring having spaced indentations below the top edge of the vessel, a cap remover having an end held in said indentations within the confines of the cap when the cap is applied to the vessel, and a neck ring on said bottle beneath the mouth ring having a shoulder at its upper edge designed to engage the lower edge of the cap when in operative sealing position on the vessel.

50. 11. In combination with a vessel having a mouth ring adapted to receive a skirted cap, said mouth ring having spaced indentations below the top edge of the vessel, a cap remover having an end held in said indentations within the confines of the cap when the cap is applied to the vessel, and a neck ring on said bottle beneath the mouth ring having a shoulder at its upper edge designed to engage the lower edge of the cap when in operative sealing position on the vessel, said neck ring having grooves in the wall thereof to receive said remover.
